UNITED STATES PATENT OFFICE.

JOHN F. RAHN, OF THORNTON, ILLINOIS, ASSIGNOR OF ONE-HALF TO JOHN C. GUSTAFSON, OF CHICAGO, ILLINOIS.

RAILWAY-TIE.

1,206,375.

Specification of Letters Patent. Patented Nov. 28, 1916.

Application filed April 5, 1915. Serial No. 19,160.

To all whom it may concern:

Be it known that I, JOHN F. RAHN, citizen of the United States, residing at Thornton, in the county of Cook and State of Illinois, have invented a certain new and useful improvement in Railway-Ties, of which the following is a full, clear, concise, and exact description.

This invention relates to railway ties and more particularly to composite ties, that is, ties made of concrete or other similar plastic material reinforced by metal. Its object is to provide an inexpensive tie of the character described which is of light weight, which will not become center-bound, and in which the tendency of the tie to crack or break is greatly lessened.

A further object is to provide a tie in which the reinforcing bars are so disposed as to insure increased strength and are also protected from exposure to the weather.

A further object of the invention is to provide a tie having a novel rail seat, the seat being so constricted as to prevent the crumbling of the concrete and to permit of ready and facile attachment of the fastening means by which the rails are secured to the ties.

With the above mentioned objects in view, one feature of my invention consists in providing a tie having flat undersurface at its opposite ends and an intermediate portion of less width at its under side than at the ends. The ends of the ties are preferably of rectangular cross-section and the intermediate portion is preferably of triangular cross-section.

Another feature of the invention consists in providing longitudinally extending reinforcing bars, some of which are arched upwardly at their center but are embedded throughout their length in the concrete.

Another feature of the invention relates to the rail seat which consists of a metallic strap or the like encircling the end of the tie and embedded in the concrete with the outer surface of the strap flush with the surface of the tie.

Another feature consists in slotting the rail seat upon the opposite sides of the tie so that the securing bolts or similar fastening devices may be inserted from opposite sides of the tie, a portion of the concrete

of the tie being likewise slotted to receive the securing devices.

Other features relate to the various details hereinafter more particularly pointed out.

The invention may be more readily understood by reference to the accompanying drawings, in which—

Figure 1 is a side elevation of a tie embodying the invention, with the rails seated thereon shown in cross-section; Fig. 2 is a top, plan view of the tie; Fig. 3 is an enlarged section on the line 3—3 of Fig. 1; Fig. 4 is an enlarged, fragmentary view of one of the two similar opposite ends of the tie; and Figs. 5 and 6 are sections on the lines 5—5 and 6—6 of Fig. 4.

Like letters of reference refer to like parts throughout the several views.

The body of the tie is made of concrete or other suitable plastic material reinforced by metallic bars, and is homogeneous throughout its length. At its opposite ends 1, 1, the tie is of approximately rectangular cross-section, thus providing a flat undersurface which rests upon the road bed. Intermediate said end portions is a central or intermediate portion 2 having a sharp lower edge 3, such intermediate portion being of approximately triangular cross-section with the vertex of the triangle resting upon the road bed. By reason of this structure the tie does not become center-bound. As is well known, the weight upon railway ties is greatest at the opposite ends thereof, hence there is a tendency for the ends of the ties to become embedded in the road bed to a greater extent than the central portion. The central portion of the tie thus becomes center-bound and it is necessary, with the usual type of tie, from time to time to tamp the material underneath the opposite ends of the tie in order that said ends may rest firmly upon the road bed.

In the case of the present invention, the sharp edges of the central portion of the tie permit of such central portion being depressed an amount corresponding to the depression of the ends, and hence the tie rests uniformly upon the road bed.

In the case of composite ties of the usual type, there is a tendency of the tie to break at its intermediate portion, since the increased weight upon the ends of the tie puts

so great a transverse strain upon the tie that the concrete cracks at such center portion. In the case of the present invention the tie is partially protected against such strain by the shape of certain of the reinforcing bars 4, 4, and moreover the strain is furthermore greatly decreased by reason of the fact that the tendency of the tie to become center-bound is provided against. The reinforcing bars 4, 4 may be in the form of straight bars extending from one end of the tie to the other, except that those of the bars which if straight would not at their central portion be embedded in the concrete are bent 15 upward as at 5 so that they will be embedded in the concrete. In the drawings two of the reinforcing bars 4, 4 are arched at their centers, the ends of the bars being embedded in the bottom of the ends of the tie and 20 the central portion of the bars being embedded in the upper surface of the central portion of the tie. The arch-like structure of the reinforcing bars thus greatly adds strength to the tie, and also permits of the 25 bars being completely embedded in the concrete. It is obvious that as many of these reinforcing bars may be provided as may be deemed necessary for strength, and that where the bars, if extended straight, would 30 emerge from the concrete at the center of the tie, they will be bent so as to remain embedded in the concrete.

At each of the opposite ends of the tie is a rail seat consisting of a rectangular strap 35 composed of an upper plate 6 and a lower plate 7 which extend transversely of the tie and are connected at their opposite ends by vertical flanges 8. The plates 6, 7 and the flanges 8, 8 have their outer surfaces flush 40 with the outer surfaces of the tie. The rail seat is thus in the nature of a band which completely encircles the tie. Upon opposite sides of the tie and upon opposite sides of the rail 9, slots 10 are provided in the rail 45 seat, such slots also extending into the concrete. These slots are provided in order that the bolts 11 may be inserted from the opposite sides of the tie. At the lower end of the slot the plates 7 have an arched portion 12 which provides a socket or seat on its under side for the reception of the head 12 of the bolt, the lower end of the bolt being thus flush with the undersurface of the tie. The upper end of the bolt receives a fastening 50 clip 13, which is held upon the end of the bolt by the nut 11. One end of the clip 13 extends over the flange of the rail and its opposite end is provided with a downwardly extending flange 15 which is seated in a

groove 16 provided in the upper surface of 60 the plate 6. Therefore, when the nut 11 is screwed down, the clip 13 is securely clamped in position and the bolts 11 are securely held against lateral movement. With the structure shown and described the head of the 65 bolt does not bear against the concrete of the tie and hence the bolt, however tight it may be drawn, will not cause the concrete to crumble. Moreover, since the bolts slip in from the side of the tie, they may be readily 70 inserted or removed and the fastening clip 13, in addition to holding the rail in place, also holds the bolt in its desired securing position.

It will be understood that the invention is 75 not limited to the specific structure shown and described and that modifications in the various details thereof may be made without departing from the scope of the invention as defined in the accompanying claims. 80

What I claim is:

1. A railway tie of plastic material having a rail seat consisting of a metallic band encircling the tie, said band being slotted at its opposite ends for the reception of rail 85 fastening devices.

2. A railway tie of plastic material having a metallic band encircling the tie and embedded in said plastic material, said band and said tie being provided with a pair of 90 vertical slots upon the opposite sides of the tie for the reception of rail-fastening devices.

3. The combination of a railway tie of plastic material, a rail seat comprising a 95 metallic band encircling the tie and embedded in said plastic material, the under surface of said band having a socket, a bolt having a head seated in said socket, and means carried by said bolt for securing a 100 rail upon said seat.

4. The combination in a railway tie of plastic material, of a rail seat comprising a metal plate on the top and bottom of said tie, said lower plate having a socket and said upper plate having a slot, a rail flange engaging clip resting on said upper plate and having a projection received within said slot, and a bolt having a head seated in said socket passing through said tie and through 110 openings in said plates and through said clip, and a nut on said bolt above said clip whereby said bolt and clip serve to secure a rail upon said seat.

In witness whereof, I hereunto subscribe 115 my name this third day of April, A. D. 1915.

JOHN F. RAHN.
